WINDOW SHADE

Filed May 27, 1929

INVENTOR:

John Heald,
O. Martin,
ATTORNEY.

BY

UNITED STATES PATENT OFFICE

JOHN HEALD, OF PASADENA, CALIFORNIA

WINDOW SHADE

Application filed May 27, 1929. Serial No. 366,244.

This invention has relation to window sun shades and refers particularly to improvements in ventilating roller shades. The general object of the invention is the provision of a roller shade of simple and inexpensive construction, which is capable of arresting sunlight and at the same time to admit an abundant supply of air. With this object in view my invention consists in the combinations hereinafter fully described and illustrated in the accompanying drawing, of which:

Fig. 1 illustrates a ventilating roller shade embodying the invention,
15 Fig. 2 is a cross sectional end elevation of the structure, and

Fig. 3 shows a modified form of device. The structure of my invention comprises a shade roller 1 of any well known standard construction, to which two rows of overlapping strips of shade cloth 2, 3 are attached. These strips may all be alike. The strips 3 are first mounted on the roller in uniform spaced relation, whereupon the strips 2 are fastened on top of the former in similar spaced relation but so that each strip 2 covers a space between two of the strips 3.

A spreader bar 4 is placed between the two rows of strips in close proximity to the roller, 30 and this bar may conveniently be hung on the pivots of the shade roller, substantially as indicated in the drawing, or it may, of course, be mounted on the window frame supporting the roller, in the proper relation thereto. The lower ends of the strips are fastened to a suitable cross bar 5 in any convenient manner. The spreader bar 4 and the bottom bar 5 are preferably made the same width and may be as wide as the roller so as to afford ample 40 space between the two rows of strips.

The width of the strips in relation to the width of the openings between the strips should be so proportioned that no slanting ray of sunlight may pass through the openings of the two rows. As the two rows of strips are shown in Fig. 1 such rays may pass through the space 6 and the space 7, but this is done merely for the sake of clearness of illustration. In actual practice, where it is desired to cut out sun rays entirely, the open-

ings between all the strips must be so narrow relative to the width of the strips that this cannot happen.

The structure of Fig. 3 comprises two shade rollers 10, 11, one mounted directly above the other and each carrying one row of strips 12, 13. The rollers and strips may all be alike, the only difference between the two being, that the strips on one roller are mounted clockwise and on the other anticlockwise, whereby an effect is produced similar to that above described. In this case no spreader bar is required, but as an extra roller with its mountings is needed, this structure is, perhaps, not as inexpensive as the one above described.

The advantage of this modified device is that each of the shades may be operated independent of the other. In case more light is desired, the one may be lowered more than the other. Also that one may be replaced without disturbing the other.

Because of the many different widths of windows it is common practice to trim the side edges of the shade cloth to the size desired, leaving such trimmed edges unprotected and apt to unravel. With my device it is possible to carry strips of standard sizes and, where there is a variation of a few inches in the width of the shades, to vary the space between the strips slightly. If, for example, a one-yard shade is required, four six-inch strips may be employed in each row with three-inch spacing between the strips, and one three-inch space at one end of each row. Should now a thirty four inch shade be required, it is only necessary to reduce each space by one-half inch, all the strips remaining the same.

It is also possible with my device to use strips of different colors and ornamentations, and thereby to provide a great number of desirable decorative effects not obtainable in ordinary shades without incurring great expense.

I claim:

1. In a sun shade device, two rows of strips of shade cloth, each of which is fastened to a roller of the device at one end and to a cross bar of the device at the other end, the strips of each row being uniformly spaced.

apart and so related that the strips of one row cover and overlap the spaces between the strips of the other row, and means maintaining one row spaced apart from the other row.

- 5 2. The combination with a shade roller, of a row of shade cloth strips mounted on said roller and uniformly spaced thereon, a second row of strips mounted on the roller to cover the spaces between the strips of the first row, means mounted close to the roller for maintaining the two rows of strips spread apart, and a cross member to which the free ends of the strips are fastened, the strips of the two rows being bent around said member from opposite sides.
- 10 3. The combination with a shade roller, of two rows of shade cloth strips mounted on said roller, the strips of one row covering and overlapping the spaces between the strips of the other row, a member hung on the pivots of the roller and capable of maintaining the two rows spread apart, and a member to which the free ends of both rows of strips are fastened from opposite sides.
- 15 4. In a roller shade, two rows of shade cloth strips forming two barred curtains positioned one behind the other, the strips of one curtain covering the spaces between the strips of the other curtain, means on which said curtains are wound for raising and lowering, and means maintaining the two curtains spaced apart.
